Attorney

UNITED STATES PATENT OFFICE.

JOHN DEXTER, OF NEW BEDFORD, MASSACHUSETTS.

CONDENSER FOR TEXTILE FIBERS.

1,416,339.

Specification of Letters Patent. Patented May 16, 1922.

Application filed March 30, 1920. Serial No. 369,833.

To all whom it may concern:

Be it known that I, JOHN DEXTER, a citizen of the United States, and a resident of New Bedford, county of Bristol, and State 5 of Massachusetts, (whose post-office address is 115 Orchard Street, New Bedford, Massachusetts,) have invented an Improvement in Condensers for Textile Fibers, of which the following description, in connection with 10 the accompanying drawings, is a specification, like characters on the drawings representing like parts.

This invention relates to rub aprons used in connection with carding machines for im- 15 parting to a ribbon of fibers a rounded or cylindrical form.

In machines of this general type, the ribbons of fibers are subjected to a rolling or rubbing action between aprons usually 20 formed of leather or the like. The aprons are given an advancing movement in unison to advance the ribbons of fibers, and simultaneously therewith the aprons have im- 25 parted thereto a reciprocating transverse movement in short paths so that as the ribbons of fiber pass between the aprons they are caught and formed into a cylindrical shape.

During treatment, the fibers will absorb 30 to a more or less degree, the oily or lubricant matter contained in the aprons, the surface of which soon become dry and smooth or glazed, with the result that they fail to perform their condenser functions. Under 35 these conditions, it is necessary from time to time to stop the machine and apply an oily or lubricating substance to the surface of the aprons. This results in loss, and the character of the slivers or rovings produced 40 varies progressively from the time when the aprons are first lubricated until the next lubrication takes place. If the aprons are run for a time without properly forming the slivers or rovings, a loss due to the improper 45 formation of the slivers or rovings results, causing waste and inferior work. A feature of the present invention, therefore, consists of means for automatically supplying a proper lubricant to the surface of the 50 aprons and regulating that supply of lubricant to maintain the desired condition of the surface of the apron that they may perform their condensing functions uniformly throughout the entire length of the slivers 55 or rovings being produced.

Other features of the invention and novel combination of parts will be hereinafter described in addition to the above, and in connection with the accompanying drawings which show one good, practical form of the 60 invention, wherein:

Figure 1 is a perspective view showing a leather apron condenser with the present invention associated therewith;

Fig. 2 is a perspective view of certain 65 features of the invention shown detached from the condenser;

Fig. 3 is a longitudinal section of the condenser apron lubricating means, some of the 70 parts being broken away;

Fig. 4 is a cross section of the lubricating device on the line 4—4 of Fig. 3; and

Fig. 5 is a detail of a modified form of trough support.

The invention may be advantageously applied to any of the rub aprons employed in connection with carding machines for forming ribbons of fiber into cylindrical form or into what is technically known as "slivers" or rovings. In the present instance, it is 75 shown as applied to the rub aprons connected with a condenser and it will be convenient to describe it in that connection, with the understanding that it may be advantageously employed in connection with any 80 of the rub aprons used to form ribbons of fibers into cylindrical form.

The condenser frame may be of any suitable character for supporting the operating parts, and in the present instance of the invention, comprises the side frames 1 which are connected by the cross tie 2, one or more of which may be employed, as the circumstances dictate. Supported by the condenser frame, in the present instance, are shown 90 two rub aprons which are mounted upon suitable rolls driven as usual, to impart to the aprons an advancing or feeding movement. At one end of the rub apron supporting and operating rolls, means are provided 95 for giving the aprons a reciprocating movement transversely to their feeding movement, the construction being such that the fibers delivered to the aprons from the carding machine may be properly rolled into 100 cylindrical form. Referring more particularly to the construction as herein illustrated, the upper pair of aprons 3 and 4, are mounted upon rolls 5 and 6 which extend 105 transversely of the frame and are journaled 110

in suitable bearings 7, so that the contiguous surface of the upper and lower aprons may be sufficiently close to impart to the fibers the feeding and rolling movements. On the 5 ends of the rolls 5 and 6 are the tooth wheels or gears 8 which may be driven from a suitable source of power to impart to the aprons 3 and 4 their feeding movements, as usual.

In addition to the support of the rolls 5 10 and 6, the aprons 3 and 4 pass around the rolls 9 and 10 which are carried in bearing blocks 11 mounted for adjustment toward and from the bearings 7 to properly adjust the tension of the aprons. The construction 15 thus far described may be of the usual character in this class of machines, or may be varied to suit conditions of use.

Below the upper pair of aprons 3 and 4 are the lower condenser aprons 12 and 13, 20 which are mounted upon the rolls 14 and 15 in a manner similar to the upper pair of aprons, and the lower pair of aprons may be driven as usual, through the gears or pinions 16. The construction and arrangement 25 of the upper and lower pairs of aprons are similar, or may be, and the description of the upper pair of aprons as herein recited, may be applied with equal force to the lower pair of aprons.

30 The several rub apron supporting rolls have their other ends supported in a frame 17 which is given a reciprocating movement transversely of the machine by any suitable means. In the present instance, the frame 17 is given its reciprocating movements from the eccentrics 18 and 19 mounted on the operating shaft 20, the construction being such that the aprons will be given their feeding movements through their respective rolls 5, 40 6, 14 and 15 and their lateral reciprocating movements by the reciprocating frame 17. The parts thus far described may be of usual construction, and need no further elucidation. The ribbons of fiber 21 enter between 45 the associated pairs of aprons and, owing to the feeding and lateral reciprocating movements of the aprons, the ribbons of fiber emerge from the aprons in the form of slivers or rovings 22.

50 As hereinbefore pointed out, where the rub apron system is employed for treating fibers, the surfaces of the apron soon become dry and smoothed or glazed. The progressive drying and smoothing or glazing of the surface 55 of the aprons from the commencement toward the end of their operation necessarily cause a variation in the character of the slivers or rovings produced, because, when the aprons are properly conditioned by the 60 lubricant, their grip upon the cotton fibers is more emphasized than when the surface of the aprons become more or less devoid of lubricant, or approach the dry or glazed condition. The result of this is that the 65 slivers produced by the aprons are not uni-

form in character from the start to finish, and toward the end of the operation, when the surface of the aprons approach the dried, smoothed or glazed condition, the slivers or rovings fail to be properly produced, and such end portions of the slivers become waste, and must be retreated by passing through the carding machine and being incorporated with other fibers.

The present invention therefore contemplates the provision of means for obviating this progressively-defective condition of the slivers or rovings by supplying to the apron automatically and continuously during the rubbing operation, a suitable amount of lubricant, and one good form of means to this end consists of a trough-like receptacle extending transversely of the rub aprons and having a lubricating device which normally contacts with the surface of the associated 85 apron of each pair.

In the present instance the lubricant-supplying means consists of a trough 23 having the downwardly-inclined side portions 24 and a cover 25, the trough being supported 90 from the condenser frame by suitable means such as the hangers 26 and 27. The hangers 26 and 27 may be secured to the side frames by suitable securing means such as the bolts 28 and have their opposite end portions connected to the lubricating trough 23, the construction being such that the bolts 28 may be readily detached to permit the lubricating trough to be taken from the machine.

In some cases it may be desirable to more 100 readily move the lubricating trough and be able to replace it without the necessity of adjustment and use of tools, so that those unfamiliar with mechanisms may remove the lubricating trough and then replace it in 105 proper position. In such cases the end portions of the lubricating trough may each be provided with a bracket or leg 49, Fig. 5, having a foot portion 50 which may rest upon an adjusting screw 51 extending 110 through the lower portion of a supporting bracket 52 which may be secured to and depend from the inner side of the frame, as indicated in Fig. 5. The bracket 52 may have the guide portions 53 to receive between them 115 the leg 49 and the foot 50.

The trough 23 is supplied with a lubricant from a suitable container which, in the present instance of the invention, consists of a reservoir 29 conveniently supported by a bracket 30 from the condenser frame, to which the bracket is secured by a detachable bolt 31, the construction being such that the reservoir may be readily detached from the condenser frame.

It will be understood that a lubricating trough 23 is provided for each pair of rub aprons and each of the lubricating troughs is connected to the reservoir 29 by a supply pipe 32. The supply pipe 32 extends pref- 130

erably longitudinally of the lubricating troughs and is provided with a series of outlets 33 within the lubricating troughs, the end of the supply pipe at 34, Fig. 3, being closed, the construction being such that the lubricant will be supplied with substantial equality throughout the length of the lubricating troughs.

The supply of lubricant to the supply pipes 32 may be controlled by suitable means which enables the quantity of lubricant delivered to the troughs to be regulated at will. In the present instance, each of the lubricating troughs has extending thereinto and surrounding the portion of the supply pipes 32 within the troughs, a rotary cover 35 which, like the supply pipes themselves, is provided with a series of outlets 36. The end of the cover 35 projects beyond the end of the lubricating troughs and is provided with a boss 37 by which the cover 35 may be rotated or moved about the perforated portion of the supply pipes, the construction being such that the outlets 33 of the supply pipe and outlets 36 of the cover may be adjusted to regulate the quantity of lubricant delivered to the lubricating troughs. As a convenient means for maintaining the cover 35 in its operative position, it may be threaded at 38 into a bearing 39 projecting from the end of the lubricating troughs.

At its delivery end, each of the lubricating troughs is provided with a lubricant distributor 40 preferably formed of a substance which will permit the slow passage of lubricant therethrough, such as a wick or the like; and in order that the delivery of lubricant by the distributor may be further regulated to suit the conditions of use, the lower end portion of the delivery troughs is provided with a flexible wall 41 which may be made to bear with more or less energy upon the distributor by means of a series of adjusting bolts 42. The delivery end portion of each trough is preferably reinforced, also, by angle irons or strengthening members 43 to provide equal distribution of pressure on the wick. Within the lubricating trough and preferably extending to or above the outlets of the delivery pipes 32 there is provided the absorbent material 44 which may be formed of some textile fiber such as cotton, wool or the like, the construction being such that the lubricant supplied to the lubricating troughs will gradually work downward to and be transmitted by the distributor 40 to one surface of each pair of rub aprons, substantially as indicated in Fig. 1, and the supply of lubricant will be automatic throughout the operation of the machine, and of a quantity to maintain the surface of the aprons in proper condition for performing their sliver or roving-forming func-

tions. Thus the entire length of slivers produced by the rub aprons are made uniform in character from start to finish, and waste of material, as well as of labor and lubricant, is obviated.

Of course it will be understood that variations may be made in the particular means for properly supplying and distributing the lubricant to the aprons automatically, and if desired, the shut-off cocks 45 and 46 may be placed in the supply pipes 32 for interrupting the supply of lubricant, should such interruption be found desirable.

In the illustrated form of the invention, the lubricating trough for supplying the lubricant automatically to the lower pair of condenser aprons is supported by the brackets 47 which are adjustably secured by the bolt and slot connection 48 to the side of the condenser frame.

While the lubricant is continuously and automatically supplied to only one of the condenser aprons, such lubricant is itself transferred to the surface of its companion condenser apron by the fibers which pass between the aprons and also by contact of the aprons themselves.

What is claimed is—

1. In a condenser provided with rub aprons, means for applying oil to the sliver-engaging surface of said aprons, comprising, in combination, a lubricant trough supported transversely of and in spaced relation to an apron, a flexible lubricant distributor extending lengthwise of the trough and protruding from the trough in the direction of the apron, lubricant supply means extending longitudinally within said trough and having outlets for the lubricant at spaced intervals within the trough, and adjustable means cooperating with said outlets to regulate the flow of lubricant therefrom.

2. A lubricant device for supplying lubricant to a traveling apron, comprising, in combination, a lubricant trough having a longitudinally-extending slot leading from the lower portion of the trough, means for supporting the trough transversely of and in spaced relation to the apron, a lubricant wick within said slot and extending therefrom toward the traveling apron, and adjustable means adjacent said slot and adapted to pinch the wick to vary the amount of lubricant delivered by the wick to the apron.

3. A lubricant device for supplying oil to a traveling condenser apron, comprising in combination, a lubricant trough containing oil-absorbing material and having a longitudinally-extending slot leading from the lower portion of the trough, means for supporting the trough in spaced relation to the apron, an oil wick within said slot and extending therefrom into engagement with the condenser apron, and adjustable means for moving one of the walls of said slot

toward the other to pinch the wick and thereby vary the amount of oil supplied by the wick to the apron.

4. A lubricant device for supplying oil to a condenser apron, comprising, in combination, a lubricant trough having a slot extending longitudinally thereof and leading from the lower portion of the trough, means for conducting oil from said slot to an apron, a reservoir for the oil positioned externally of the trough, a conduit leading from the reservoir and extending into the trough and longitudinally thereof and provided with a series of outlets for the oil, and adjustable means for varying the effective size of said outlets to control the amount of oil passing through the outlets.
5. A lubricant device for supplying oil to a condenser apron, comprising in combination a lubricant trough having an adjustable outlet constructed to extend across a condenser apron, means for supporting the trough in spaced relation to the apron, a flexible distributor extending through the outlet toward the apron to conduct oil thereto, and means for adjusting the width of said outlet to squeeze the flexible distributor and thereby control the amount of oil supplied to the apron.

6. A lubricant device for supplying lubricant to a traveling apron, comprising, in combination, a lubricant trough, a lubricant supply conduit extending longitudinally within the trough and having outlets for the lubricant at spaced intervals within the trough, adjustable means cooperating with said outlets to regulate the flow of lubricant therefrom, and a lubricant distributor disposed longitudinally of said trough and extending therefrom to conduct lubricant to the apron.

7. A condenser apron oiler, comprising, in combination, a lubricant trough having a longitudinally-extending slot leading from the lower portion of the trough, means for supporting the trough in spaced relation to

the apron and adjustable to vary the position of the trough relative to the apron, a lubricant wick within said slot and extending therefrom toward the traveling apron, and means for adjustably pinching the wick to vary the amount of lubricant delivered by the wick to the apron.

8. A lubricant device for supplying oil to a traveling surface, comprising in combination, a lubricant trough containing oil absorbing material and having a longitudinally-extending slot leading from the trough, an oil wick within said slot and extending therefrom toward the traveling surface to supply oil to the surface, and adjustable means for pinching the wick to thereby vary the amount of oil supplied by the wick to the traveling surface.

9. A lubricant device for supplying oil to a traveling web, comprising in combination, a lubricant trough having a longitudinally-extending slot leading from the trough, an oil wick within said slot and extending therefrom toward the traveling web to supply oil to the web, and adjustable means for pinching the wick to thereby vary the amount of oil supplied by the wick to the traveling web.

10. A lubricant device for supplying oil to a traveling surface, comprising, in combination, a lubricant trough having a longitudinally-extending slot leading from the lower portion of the trough, an oil wick within said trough and extending therefrom toward the traveling surface to supply oil to the surface, means for pinching the wick to thereby control the amount of oil supplied by the wick to the traveling surface, and oil-absorbing material packed in the trough adjacent the wick to retard by capillary attraction passage of oil within the trough to the wick.

In testimony whereof, I have signed my name to this specification.

JOHN DEXTER.
